UNITED STATES PATENT OFFICE.

JOHAN KOFOED, OF CHRISTIANIA, NORWAY.

DUPLEX STEAM-PUMP.

No. 830,723.

Specification of Letters Patent.

Patented Sept. 11, 1906.

Application filed January 9, 1906. Serial No. 295,235.

To all whom it may concern:

Be it known that I, JOHAN KOFOED, a subject of the King of Norway, residing at Christiania, Norway, have invented certain new and useful Improvements in Duplex Steam-Pumps; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

My invention relates to duplex steam-pumps; and it has for its object to provide a valve mechanism therefor which will materially increase the efficiency of the pump or engine, promote its durability, and secure a considerable saving in the steam used to operate the same.

To these ends my invention consists in the valve mechanism constructed and operating as hereinafter fully described, and particularly pointed out in the claims.

Referring to the drawings, in which like numerals designate like parts in the several figures, Figure 1 is a cross-section of a direct-acting duplex steam-pump embodying my invention, taken at the lines 1 1 of Fig. 2. Fig. 2 is a vertical longitudinal section thereof taken at line 2 2 of Fig. 1. Fig. 3 is a plan view of the valve and its operating-cams. Fig. 4 is a cross-section of the two piston-rods and the valve-rod, an end view of one of the cam members on said valve-stem, and a side view of the two arms which actuate said cam members. Figs. 5, 6, and 7 are cross-sections of the valve-chest and valve taken at lines 5 5, 6 6, and 7 7 of Fig. 2. Fig. 8 is an end view of the valve-rod, and Figs. 9 and 10 show details of the same.

The numerals 1 and 2 designate the two steam-cylinders, 3 and 4 the two piston-heads, and 5 and 6 the two piston-rods of a common form of duplex steam-pump, the water end of said pump being not shown, as its construction and mode of operation are well known. 7 and 8 are actuating-arms on the piston-rods. In lieu of the various forms of slide and other valves heretofore employed for admitting steam to and exhausting it from said cylinders 1 and 2, I have devised a single revoluble valve for performing such function, together with means for

transmitting a revolving movement to said valve from the piston-rods 5 and 6, and will now proceed to describe the same.

Between the steam-cylinders 1 and 2 is located a valve-chamber 13 of cylindrical shape, in which chamber is centrally located the cylindrical valve 16, said valve being capable of a free revolving movement within the chamber and having the valve-rod 26 projecting therefrom through one of the end walls or heads of the chamber.

9 10 and 11 12, respectively, are the steam-ports between the two cylinders and the valve-chamber 13 common to both of them.

14 is the live-steam inlet, and 15 the exhaust-opening. In the valve 16 is formed a central passage 17 for the exhaust-steam, while the space outside of the valve forms the passage for the live steam. The exhaust-passage 17 terminates at each end of the valve in two diametrically-opposed ports 18 19 and 20 21, respectively, which at certain positions of the valve correspond with the ports of the steam-cylinders. Between said exhaust-ports there are in the valve at each end formed live-steam ports 22 23 and 24 25, respectively, which open in the live-steam space of the valve-chamber, and at given positions of the valve correspond with the ports of the steam-cylinders.

Upon the valve-rod 26 are secured two 85 cam members, each of which consists of a split collar embracing said valve-rod, from the end of which cam members project two oppositely-located fingers 27 28 and 29 30, respectively, each of said fingers having one 90 of its side edges parallel to the axis of said valve-rod and its opposite edge at an angle thereto. The fingers of the two cam members project toward each other and terminate at a point substantially midway between said members. As shown in Fig. 3, the fingers 27 28 of the one cam member are offset at an angle of ninety degrees with respect to the fingers 29 30 of the other cam member; but in order to enable such relative 100 position to be varied for the purpose of varying the point in the stroke at which the cut-off will occur I may make said cam members adjustable about the axis of the valve-rod. I prefer, however, to make use of an adjustment device, as shown in Figs. 2 and 3 and Figs. 8, 9, and 10. In the adjustment device shown means are provided whereby the

valve and the valve-rod may be turned relatively to each other by means of a hand-wheel 40 during the operation of the pump.

The valve 16 and its rod 26 abut against each other with plane end faces. The valve-rod terminates in a head 31, in which is drilled a cavity 32, taking up a spring 33. Through the head are inserted two pins 34, between which is formed a guide for a coupling member (shown in Figs. 9 and 10) having a part 35, corresponding in shape to the guide-space between the two pins 34, said part 35 being of a twisted form. The head 36 of the coupling member has a rectangular shape and fits into a similarly-shaped notch 37 in the end of the valve-body. In the head 36 is secured a long rod 38, which abuts against a screw 39, carrying the hand-wheel 40; by means of which the screw may be screwed out. If the screw 39 is turned, it will allow the rod 38 to move outward; and the spring 33 will press the coupling member 35, 36 outwardly, and on account of the twisted form of the part 35 this movement will cause a turning movement of the valve relatively to the valve-rod.

The operation of the valve is as follows: The valve is caused to rotate in one and the same direction, thereby alternately admitting steam to the two steam-cylinders. In the position of the parts shown in Fig. 2 the steam is passing into and out of the cylinder 2, as indicated by arrows. The actuating member 8 is then moving to the left and will in the moment shown be about to hit the cam 27, whereby steam will be successively cut off from the cylinder 2 and before the piston in this cylinder has come to its extreme position the valve will have been turned so much that steam is admitted into the cylinder 1 at its left end. The piston of that cylinder will then move to the right in Fig. 2 and the actuating member 7 will, when it has passed half-way of the stroke, hit the cam 30 and cause a new turning movement of the valve, whereby steam will be admitted in the cylinder 2 on the left side of the piston, and so on. The required degree of expansion of the steam may be regulated by means of the hand-wheel 40.

50 I claim—

1. In combination with the steam-cylinders, pistons and piston-rods of a duplex steam-pump, of a valve-chamber common to said steam-cylinders and connected therewith by steam-passages, a valve revolvably arranged within said chamber and provided with steam-passages and having its stem projecting beyond the said chamber, cams on said stem and means on the piston-rods adapted to alternately engage said cams on said stem so as to impart an intermittent rotary movement to the valve in one and the same direction, thereby alternately admitting and exhausting steam to and from the said steam-cylinders respectively.

2. The combination with the two steam-cylinders, pistons, and piston-rods of a direct-acting, duplex steam-pump, of a steam-chest having a revolvble valve provided with passages adapted to register with the steam inlet and exhaust passages of both of said cylinders, said valve having its axis extended beyond the valve-chamber in a plane parallel with said piston-rods and having said axis provided with a plurality of spirally-disposed surfaces, of an engaging device mounted upon each of said piston-rods for engaging said spirally-disposed surfaces in both directions of movement of said rods to impart a revolving movement to said valve, substantially as described.

3. The combination with the steam-cylinders, pistons and piston-rods of a direct-acting, duplex steam-pump of a steam-chest containing a revolvble valve having passages for registering with the steam inlet and exhaust passages of said cylinders, said valve having its operating-stem projected in a plane parallel with said piston-rods and having mounted upon said stem two oppositely-projecting cam members and two engaging arms upon said piston-rods for engaging said cam members to impart a revolving movement to the valve, substantially as described.

4. The combination with the steam-cylinders of a duplex steam-pump and their pistons, of a cylindrical valve-chamber the axis of which is parallel with the axis of said steam-cylinders and which is connected by a passage at each of its ends with the corresponding ends of said cylinders, a cylindrical valve located within said chamber and having its operating-stem provided with two oppositely-inclined surfaces, and contact devices carried by the steam-pistons which are adapted to alternately engage said inclined surfaces on said stem and thereby impart an intermittent revolving movement to the valve in one and the same direction, substantially as described, and means to adjust the stem with its inclined surfaces relatively to the valve.

5. The combination with the steam-cylinders of a duplex steam-pump and their pistons, of a cylindrical valve-chamber the axis of which is parallel with the axis of said steam-cylinders and which is connected by a passage at each of its ends with the corresponding ends of said cylinders, a cylindrical valve located within said chamber and having its operating-stem provided with two oppositely-inclined surfaces, and contact devices carried by the steam-pistons which are adapted to alternately engage said inclined surfaces on said stem and thereby impart an intermittent revolving movement to the valve in one and the same direction, substantially as described, and means to adjust the stem with its inclined surfaces relatively to the valve, said means consisting of an axially-

movable coupling member, having a straight part engaging the valve and a twisted part engaging the valve-stem, a spring pressing the coupling member outwardly from the 5 valve-stem and a screw-spindle adjusting the position of the coupling member relatively to the valve and the valve-stem.

In testimony that I claim the foregoing as my invention I have signed my name in presence of two subscribing witnesses.

JOHAN KOFOED.
